UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,333,758.

Specification of Letters Patent. Patented Mar. 16, 1920.

Application filed May 24, 1917. Serial No. 170,602.

To all whom it may concern:

Be it known that I, CHARLES W. KECKLER, a citizen of the United States, residing at Newark, in the county of Essex and State of New Jersey, have invented certain new and useful Improvements in Telephone Systems, of which the following is a full, clear, concise, and exact description.

This invention relates to telephone systems, and more particularly to such systems in which a plurality of telephone stations obtain service over a single line circuit.

The object of this invention is to enable a subscriber at one of the stations when the receiver is removed from the switchhook to obtain a clear circuit to the central office which is free from interruptions from any of the subscribers at the other stations having access to this line.

In accordance with a feature of this invention, a plurality of stations normally disconnected from a line circuit are each provided with a relay which, when energized, connects the station with the line circuit and causes the operation of a relay common to the line circuit which disables the individual relays of all other stations having access to this line. Also upon the operation of this common relay, a normally disabled source of tone signaling current is made effective for furnishing a characteristic signal to any of the other stations should the receiver thereof be removed from the switchhook while one station is connected with the line circuit.

This invention is illustrated in the accompanying drawing, in which a line circuit comprising line conductors 5 and 6 extends from a central office A. A plurality of subscribers' stations have access to this line circuit, two such stations, B and C, being shown in the drawing. Individual to each station is a relay 7, which, when energized, is adapted to connect its associated station with the line circuit. For purpose of identification the individual relay of station B will be hereinafter referred to as 7B and that for station C as 7C. A relay 8, common to the line circuit, operates upon the energization of any one of the individual relays 7 to prevent the operation of all other individual relays. A relay 9 of high resistance controlling the vibrating contact, together with a source of current,

serves as a source of tone signaling current which, on account of the back contact of relay 8 being normally closed, is normally disabled, but is rendered effective upon the operation of relay 8 to provide a busy test. 60 A slow-releasing relay 10 under the control of relay 8, when energized, maintains a locking and holding circuit for any individual relay which may be energized.

Referring to the operation of the system 65 disclosed in the drawing, it will be assumed that the subscriber of station B initiates a call by removing the receiver from the switchhook, whereupon relay 7B is energized over a circuit from battery through 70 the normal contact of relay 8, upper winding of relay 7B, contact 15 thereof, the switchhook contact and apparatus at station B, and contact 16 of relay 7B to ground. Relay 7B, in operating, establishes a locking 75 and holding circuit through its lower winding, which may be traced from battery through contact 17 of slow-releasing relay 10, lower winding of relay 7B, and contact 18 of relay 7B to ground. Upon the operation of relay 7B, relay 8 is operated over a circuit from battery 20 at the central office A, through the winding of relay 8, line conductor 5, contact 21 of relay 7B, switchhook contact and apparatus at station B, 80 contact 22 of relay 7B, and line conductor 6 back to the battery 20. Relay 8, in operating, opens its normal contact, thereby disabling the individual relays of all other stations which have access to this line circuit. 85 This is accomplished by opening the original energizing circuit, which is common to all of the individual relays, at the normal contact of relay 8, and inserting in this original energizing circuit the high resistance winding of relay 9. The resistance of the winding of this relay 9 is so high as to prevent the operation of any of the other individual relays should the receiver of the station associated therewith be removed 90 from its switchhook while individual relay 9 is in the circuit. Upon the operation of relay 8, slow-releasing relay 10 also operates, transferring the locking and holding circuit for relay 7B from the normal contact 100 17 of relay 10 to the alternate contact thereof and the alternate contact of relay 8. In operating its normal contact, relay 8 thereby removes the short circuit from relay 9 so that should the receiver at any of the 105 110

- stations (for example, station C) be removed from its switchhook while station B is connected to the line circuit, relay 9 would be intermittently operated over a circuit 5 from battery through the winding of relay 9, the vibrating contact thereof, conductor 23, the upper windings of relay 7C, and upper normal contact thereof, through the switchhook contact and primary of the induction coil at station C and the lower normal contact of relay 7C to ground. The intermittent opening and closing of this 10 circuit, due to the opening and closing of the vibrating contact of relay 9, causes a current to be induced in secondary winding 15 of the induction coil at station C, whereupon a tone is produced in the receiver at station C indicating that the line circuit is busy.
- 20 When the receiver at station B is restored to the switchhook, relay 8 releases, thereby opening a locking circuit for relay 7B, which now releases. Upon the release of relay 8, the slow-releasing relay 10 is also deenergized, whereby all apparatus is in its normal 25 position, ready for actuation by any other station having access to this line.

What is claimed is:

1. In a telephone system, line conductors, 30 a plurality of subscribers' stations normally disconnected from the line conductors, circuit leads for extending the line conductors to the subscriber's station, a switch for bridging the telephonic apparatus across the 35 circuit leads, a relay individual to each station serving when energized to complete the connection between the circuit leads and the line conductors, an energizing circuit for the individual relay including a portion of the 40 circuit leads and established upon the actuation of the switch, a locking circuit for the individual relay completed upon the energization thereof, and a common relay controlled over the line conductors by the individual relay to disable the energizing 45 circuit of all other individual relays.
2. In a telephone system, line conductors, 50 a plurality of subscribers' stations normally disconnected from the line conductors, a relay individual to the line conductors serving when energized to connect the station to the line conductors, a relay common to the line conductors, an energizing circuit therefore including a portion of the line conductors, said relay adapted when energized to 55 disable all other individual relays while the

one of said individual relays remains energized, and a normally disabled source of tone signaling current rendered effective and associated with all other stations upon the operation of the common relay. 60

3. A telephone exchange system, comprising line conductors, a plurality of subscribers' stations normally disconnected from the line conductors, a relay individual to each 65 station serving when energized to connect the station to the line conductors, a second relay common to the line conductors, an energizing circuit therefor established over a circuit including the subscriber's station, 70 said relay adapted when energized to disable all other individual relays while the one of said individual relays remains energized, and a normally disabled source of tone signaling current rendered effective and associated with all other stations upon the 75 operation of the common relay.

4. In a telephone system, line conductors, a plurality of subscribers' stations normally disconnected from the line conductors, a relay 80 individual to each station serving when energized to connect the station to the line conductors, a relay common to the line conductors and operating over a circuit including the subscriber's station upon the closure 85 of the line conductors thereat, and a disabling circuit rendered effective upon the operation of said common relay to prevent the energization of all other individual relays 90 while the one of said individual relays remains energized.

5. In a telephone system, line conductors, a plurality of subscribers' stations normally disconnected from the line conductors, a relay 95 individual to each station serving when energized to connect the station to the line conductors, a relay common to the line conductors and operating over a circuit including a subscriber's station upon the closure 100 of the line conductors thereat, a disabling circuit rendered effective upon the operation of said common relay to prevent the energization of all other individual relays 105 while one of said individual relays remains energized, and a normally disabled source of tone signaling current rendered effective and associated with all other stations upon the operation of the common relay.

In witness whereof I hereunto subscribe my name this 22nd day of May, A. D. 1917. 110

CHARLES W. KECKLER.
